Primary Examiner — Sheryl Lane*Assistant Examiner* — Stacey L Hopkins(74) *Attorney, Agent, or Firm* — Thorpe North & Western, LLP(57) **CLAIM**

The ornamental design for a flashlight, as shown and described.

DESCRIPTION

FIG. 1 is a front top perspective view of a flashlight in accordance with my invention;

FIG. 2 is a front bottom perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

Throughout the drawings the broken lines depict portions of the flashlight that form no part of the claimed design.
